UNITED STATES PATENT OFFICE.

JOHN S. NAULDER, OF PITTSBURGH, PENNSYLVANIA.

RETAINER FOR DENTAL PLATES.

1,133,570.

Specification of Letters Patent. Patented Mar. 30, 1915.

Application filed July 16, 1912. Serial No. 709,781.

To all whom it may concern:

Be it known that I, JOHN S. NAULDER, a citizen of the United States, and residing in the city of Pittsburgh, in the county of 5 Allegheny and State of Pennsylvania, have invented or discovered new and useful Improvements in Retainers for Dental Plates, of which the following is a specification.

My invention consists of a new and improved 10 retainer for holding a dental plate in place in the mouth of the wearer.

The retainer consists of a substantially ring-shaped or annular piece of thin gold, 15 tin or other non-corrosive metal whose base is secured beneath a ring-like metal flange fixed in the body of the dental plate and whose skirt extends outwardly over said flange and lies upon the surface of the dental plate. When the plate is in use, said 20 skirt becomes moist and adheres to the mouth of the wearer, securing the dental plate against accidental loosening and holding it securely yet comfortably in place, but quickly released by a sudden pull when desired. 25 The retainer is incorporated in the plate when the latter is made, but when worn out may be readily removed and a new retainer substituted.

In the accompanying drawings, Figure 30 1 is a perspective of a palatal dental plate provided with my invention; Fig. 2 is an enlarged plan of the card-board pattern; Fig. 3 is a similar view of the serrated metal disk which is divided to form the 35 flange-member and the center disk; Fig. 4 is a similar view of the thin gold or tin disk from which the retainer is formed; Fig. 5 is a plan view of the metal disk superimposed on said gold disk, the center 40 of the latter being serrated to form fingers; Fig. 6 is a similar view of the annular casing-member for the gold retainer; Fig. 7 is a similar view of the disk-shaped casing-member of said retainer; Fig. 8 is a similar 45 view showing said retainer incased in said casing-members; Fig. 9 is a similar view showing the flange member superimposed on the incased retainer, the fingers of the latter extending through the central opening of the former; Fig. 10 is a similar view 50 showing the center disk pressed back into place and the fingers of the retainer pressed

flat against the surface of the flange member; Fig. 11 is a plan view of the face-plate; Fig. 12 is a similar view showing the face-plate in position; Fig. 13 is a section along the line XIII—XIII in Fig. 1; Fig. 14 is a perspective of the plaster model with the metal base-plate mounted thereon; Fig. 15 is a similar view showing the structure 55 shown in Fig. 12 mounted on said base plate; Fig. 16 is a view similar to Fig. 1, but showing the casing still inclosing the retainer as the dental plate is lifted from the model after being vulcanized and the 60 base plate detached. Fig. 17 is a perspective of the dental plate with the retainer removed, and Fig. 18 is an inverted perspective, on enlarged scale, of the retainer.

The following is a detailed description 70 of the drawings. A is the dental plate, shown for the sake of illustration as the upper or palatal plate, but my invention is equally applicable to the lower or lingual plate when the flatness of the wearer's 75 mouth requires the retainer to hold the plate in position. I will now describe the preferred process of manufacturing the retainer and mounting the same in the dental plate during the operation of manufacturing the latter.

A piece of thin card-board 1 is cut to the proper dimensions and shape dictated by the size and contour of the dental plate. By means of wax I secure said pattern to the 85 face of a piece of metal about 30 gage and trim off the edges of the latter so that it is about $\frac{1}{8}$ inch larger than the pattern. The resulting metal disk is serrated at its edges, as at 2—2, inwardly to the edge of the pattern, the cuts being preferably alternately radial and oblique, as shown. The pattern is now detached and the center of the metal disk is cut out along a line about $\frac{1}{8}$ inch from the bases of the edge serrations 2—2, 90 forming an annular member B and a center disk C. The pattern 1 is now placed upon a sheet of thin gold, tin or similar metal, of a thickness of $1/1000$ of an inch or thinner, and the said metal, hereinafter referred to 95 as "gold" is trimmed off even with the edge of the pattern, forming a disk from which the retainer is made. The gold disk, D, is then removed from the pattern and the

annulus B superimposed thereon concentrically. I then punch a series of holes 3—3 in the disk D around the inner perimeter of the annulus B and remove the annulus. I 5 then cut out of the center of the gold disk D a small portion, as at 4, and serrate the material of the said gold disk outwardly to the holes 3—3, thus forming inwardly extending radial fingers 5—5 of substantially truncated, triangular form. The member D 10 is now in the form of an annulus having a plain circumference and a serrated inner perimeter. The member D is now placed upon a sheet of very thin metal, such as thin aluminum, and the same is punched 15 through the holes 3—3 and also trimmed around the outside even with the circumference of the member D. The center of the aluminum is now cut out around the holes punched therein, forming an annulus E. The member D is now placed upon another piece of aluminum and the same trimmed about the edge to a size about $\frac{1}{8}$ greater than the member D, forming a disk F. The member 20 D is now laid upon said disk F and the annulus E is laid upon the member D, the fingers 5—5 being bent to extend vertically through the central opening of said annulus E. The edge of the annulus E is turned up as at 6 in Fig. 8, thus inclosing said member D in a casing of very thin metal. The member B is now superimposed on the annulus E, the fingers 5—5 extending vertically through the center of said member, as shown 25 in Fig. 9. The center disk C is now replaced in the member B, being pressed down into place, the edge of said center disk and the inner perimeter of the member B having been previously smoothed so as not to cut 30 the gold. The fingers 5—5 are now bent down flat against the exposed face of the member B, as shown in Fig. 10.

G is a face plate of similar metal to member B and of the same size as pattern 1. 45 Said face plate, G, is superimposed on the member B and four or five of the serrations 2—2 are bent down flat onto said face plate to hold the elements now assembled securely together. The remaining serrations 2—2 of 50 the member B are caused to extend at an angle to the body of said member. The fingers 5—5 of the member D are held flat between the member B and the face plate G.

H, Figs. 14 and 15, is the plaster model 55 previously prepared in the usual manner and upon the same I secure by a little wax a base plate I of about 30 gage metal pressed to conform to the irregular surface of said model H. I now press the assembled elements 60 shown in Fig. 12 down snugly upon the base plate I, securing the same thereto by a little wax, the casing disk F resting upon said base plate and the face plate G being exposed. The dental plate A is then 65 molded in the usual manner upon the model

and vulcanized. When removed from the flask, the plate presents the appearance shown in Fig. 16, the aluminum casing disk F being exposed. This disk is torn away by means of a suitable tool and the annulus 70 E is also likewise removed, exposing the body or skirt of the gold retainer D which now lays extended outwardly over the portion of the flange member B not incorporated in the body of the plate A and over 75 the adjacent face of the dental plate. The center disk C is then lifted from its seat.

The presence of the base plate I when the dental plate is being molded, forms a circumferential depression in the face of the 80 dental plate A surrounding the exposed portion of the flange member B, which depression is marked 7 in the drawings. This depression is covered by the skirt of retainer D and aids in the adhering of the latter to 85 the mouth of the wearer.

The serrations 2—2 of the flange member B are securely embedded in the body of the dental plate. The conforming of the assembled elements shown in Fig. 12 to the surface contour of the base plate I and model H throw the inner perimeter of the flange member B slightly outwardly but the fingers 5—5 of the retainer D are tightly clamped between the member B and the face plate G. 90 In the center of the member B is formed a cavity 5 of a depth equal to the thickness of the base plate I, the casing disk F, and the center disk C, the bottom of said cavity being formed by the face plate G. 95

The skirt of the retainer D becoming dampened, adheres to the mouth of the wearer and holds the plate snugly in place without discomfort, but releasable by a smart jerk or pull. The retainer, being of 100 metal, does not become destroyed or offensive through the action of the acids of the mouth and is indeed indestructible except possibly by being torn through rough usage. In such case, all that is required is to insert a sharp 105 tool or stick under the edge of the exposed flange member B to lift said flange sufficiently to withdraw from beneath the same the fingers 5—5. The retainer may then be removed and a new one installed by tucking 110 its fingers 5—5 under the flange of member 8 and pressing said flange snugly down into place again.

If through the gradual shrinkage or absorption of the tissue of the mouth, the 115 plate fits too loosely, I may raise the flange of member B slightly and put a filler ring or other filling beneath the same, thereby raising the same and at the same time not interfering with the secure anchorage of 120 the fingers 5—5 of the retainer.

What I desire to claim is:—

A retainer for dental plates comprising a ring shaped metal member having its outer perimeter embedded in the plate and pre- 130

senting its inner perimeter in the form of a holding flange, and a double annulus of thin metal having its base secured under said holding flange and having its outer portion 5 trailing radially over the top surface of the plate, as and for the purpose set forth.

Signed at Pittsburgh, Penna., this 12th day of July, 1912.

JOHN S. NAULDER.

Copies of this patent may be obtained for five cents each, by addressing the "Commissioner of Patents, Washington, D. C."

It is hereby certified that Letters Patent No. 1,133,570, granted March 30, 1915, upon the application of John S. Naulder, of Pittsburgh, Pennsylvania, for an improvement in "Retainers for Dental Plates," were erroneously issued to "John S. Naulder," whereas said Letters Patent should have been issued to *Tirza Naulder, administratrix of said John S. Naulder, deceased*; and that the said Letters Patent should be read with this correction therein that the same may conform to the record of the case in the Patent Office.

Signed and sealed this 27th day of April, A. D., 1915.

[SEAL.]

J. T. NEWTON,

Acting Commissioner of Patents.
